COMBINED CARTON AND DISPLAY STAND

William Palla, Bellrose, N. Y.

Application February 9, 1933, Serial No. 655,883

14 Claims. (Cl. 206—44)

This invention relates to combined containers and/or display devices, and my improvements are directed to the production of a knock-down carton, composed of a single sheet of stiff material, such for example as cardboard, which is adapted, when folded, to contain articles of merchandise for shipment and storage, and which, when opened out, will form a stand or easel for the support and/or display of the articles of merchandise.

The single sheet of material, as formed into a blank according to my invention, is provided with integral interengaging means whereby, upon folding said blank into the form of a container or carton, said interengaging means may be interfit to fasten the enclosure.

Also said blank, when opened out, is adapted to be formed into a display stand, for the support and/or exposure of articles of merchandise, the interengaging means with which the blank is provided being adapted to interfit for the purpose of providing an erect structure whose component elements are connected in the creation thereof.

Still further the blank, when formed into a display stand, is caused to present elements thereof adapted for the display of descriptive and advertising matter relative to the exposed articles of merchandise.

Other features and advantages of my invention will hereinafter appear.

In the drawing:—

Figure 1 is a view of a blank, shaped according to my invention, for the production of the improved knock-down carton and display device.

Fig. 2 is a front perspective view of the formed carton.

Fig. 3 is a rear perspective view thereof.

Fig. 4 is a perspective front view of the carton as partly opened out in the process of creating the display device.

Fig. 5 is a similar view, with the blank elements more fully unfolded.

Fig. 6 is a rear, perspective view showing the completely formed display device, and

Fig. 7 shows an example of an article of merchandise adapted to be supported on the display device.

In Fig. 1 there appears a blank composed of cardboard or other suitable, stiff sheet material, said blank having the body or central portion 1, and the opposite side wings 2, 3, each respectively connected with the body portion by a web 4. Also an upper flap 5 is provided, it being connected with the body by a web 6; and a lower flap 7 is connected with the body by a web 8.

While the elements thus referred to are integral in the single blank, the side wings, upper and lower flaps are hinged to be capable of folding, the hinging being provided by forming creases or other weakening lines 9 at the junctions of the body and webs 4 and 8, and at the junctions of the wings 2, 3, and flaps 5, with their respective webs 4 and 8.

The wings 2, 3 are respectively provided with upper extensions 10, 11, whose upper edges, indicated at 12, are disposed at upwardly outward angles. Also the wing 3 is provided with laterally extended tabs 13, 14, and the wing 2 has V-shaped slits 15, 16 formed therein, which serve the purpose of producing, respectively, the tongues 17, 18. The tabs 13, 14 are respectively aligned, horizontally, with the tongues 17, 18, and the wing 2 in addition is provided with the laterally disposed, edge notches 19, 20 which are respectively aligned, horizontally, with the tabs 13, 14, and the tongues 17, 18.

It will be observed that the body 1 of the blank is provided with tongues 21, which are cut out from the material of said body and are folded upwardly, these tongues being intended to serve as supporting means for articles that are to be displayed, as will be described hereinafter.

The upper extensions 10, 11 of the wings 2, 3 are divided from the main portions thereof by creases or other weakening lines 22, so that said extensions may fold upon said main portions.

The wing 2 is provided with vertical slits 23, 24, the slit 23 lying in the horizontal plane which will be occupied by the tab 14 when the extension 11 is folded down upon the main portion of wing 3.

In the front view of the formed carton, illustrated in Fig. 2, the blank is shown with the webs 4, 8 and 6 folded at right angles to the body 1, the flaps 5 and 7 folded into parallel relation with the body 1, the wing extensions 10, 11 folded respectively upon the wings 2, 3, and the wings folded upon the flaps 5, 7, with the tabs 13, 14 tucked respectively in slits 23, 24, to fasten the package, which may contain articles of merchandise.

In Fig. 4 the carton is shown with the wings 2, 3, unfastened and opened out, and in Fig. 5 the wing extensions 10, 11 have been unfolded, also the flaps 5, 7.

Now, in creating a display stand or easel the wings, with their webs 4, are to be folded back until their free edges 25 meet in juxtaposition, whereupon the tabs 13, 14 become lodged and localized in notches 19, 20, and then said tabs may respectively be engaged in the slits 15, 16, to

thereby unite the elements of the stand or easel structure, whose supporting base is formed by the lower edge of body 1 and the lower edges 26 of wings 2, 3.

- 5 Since the articles to be displayed are piled against the face of body 1, to which they may be connected, it is desirable to provide a rearward centre of gravity for the stand, and therefore the wings 2, 3 are shown as having their bottom edges 10 26 formed at a rearwardly upward inclination, in order that the display stand may be rearwardly inclined and thus not liable to tip forwardly.

Suitable means may be provided for connecting the articles of merchandise to the face of body 15 1, for their display. As shown, the tongues 21 serve to engage a package of the character appearing in Fig. 7, which is in the nature of a folded box capable of engaging a tongue in a fold thereof.

- 20 In the rear view of Fig. 6 the formed display stand or easel is shown in operative position, supporting and displaying articles 27, with the flap 7 extended, to either support articles or to bear descriptive or advertising matter, and with the 25 flap 5 folded back, to lie on the edges 12 of wing extensions 10, 11, said flap 5 presenting ample surface for the exposure of descriptive or advertising matter.

Variations within the spirit and scope of my 30 invention are equally comprehended by the foregoing disclosure.

I claim:—

1. A display stand comprising a sheet of stiff material in the form of a blank having a body portion, opposite side portions, a top portion foldably extensible from said body portion, and upper extensions of said side portions that are foldable thereon, said upper extensions when folded back serving to support said top portion.

40 2. A combined container and display stand comprising a sheet of stiff material in the form of a blank having a body portion, opposite side portions, top and bottom portions foldably extensible from said body portion, and upper extensions of said side portions that are foldable thereon, said upper extensions when folded back serving to support said top portion.

45 3. A combined container and display stand comprising a sheet of stiff material in the form of a blank having a body portion, opposite side portions, top and bottom portions foldably extensible from said body portion, upper extensions of said side portions that are foldable thereon for container purposes, but when folded back serve to support said top portion, said top and bottom portions adapted to fold upon the front of said body portion, said side portions, with their extensions folded thereon, adapted to fold upon said folded top and bottom portions to constitute a container, and fastening means therefor.

50 4. A combined container and display stand comprising a sheet of stiff material in the form of a blank having a body portion, opposite side portions, top and bottom portions foldably extensible from said body portion, and upper extensions of said side portions that are foldable thereon for container purposes, but when folded back serve to support said top portion, said top and bottom portions adapted to fold upon the front of said body portion, said side portions, with their extensions folded thereon, adapted to fold upon said folded top and bottom portions to constitute a container, one of said side portions having a slit therein, and the other side

portion having a projecting tab adapted to engage said slit for fastening the container.

5. A combined container and display stand comprising a sheet of stiff material in the form of a blank having a body portion that is provided with article engaging means, opposite side portions, top and bottom portions foldably extensible from said body portion, upper extensions of said side portions that are foldable thereon for container purposes, but when folded back serve to support said top portion, said top and bottom portions adapted to fold upon the front of said body portion, said side portions, with their extensions folded thereon, adapted to fold upon said folded top and bottom portions to constitute a container, and fastening means therefor.

6. A combined container and display stand comprising a sheet of stiff material in the form of a blank having a body portion, foldable webs extending respectively from the sides, top and bottom of said body portion, foldable opposite side portions, top and bottom portions extending respectively from said webs, and upper extensions of said side portions that are foldable thereon, said upper extensions when folded back serving to support said top portion.

7. A combined container and display stand comprising a sheet of stiff material in the form of a blank having a body portion, foldable webs extending respectively from the sides, top and bottom of said body portion, foldable opposite side portions, top and bottom portions extending respectively from said webs, and upper extensions of said side portions that are foldable thereon for container purposes, but when folded back serve to support said top portion, said top and bottom portions adapted to fold upon the front of said body portion, said side portions, with their extensions folded thereon, adapted to fold upon said folded top and bottom portions to constitute a container, and fastening means therefor.

8. A combined container and display stand comprising a sheet of stiff material in the form of a blank having a body portion, foldable webs extending respectively from the sides, top and bottom of said body portion, foldable opposite side portions, top and bottom portions extending respectively from said webs, and upper extensions of said side portions that are foldable thereon, said top and bottom portions adapted to fold upon the front of said body portion, said side portions, with their extensions folded thereon, adapted to fold upon said folded top and bottom portions to constitute a container, and fastening means therefor, one of said side portions having a slit therein and the other side portion having a projecting tab to engage said slit for fastening the container, said upper extensions when folded back serving to support said top portion.

9. A combined container and display stand comprising a sheet of stiff material in the form of a blank having a body portion that is provided with article engaging means, foldable webs extending respectively from the sides, top and bottom of said body portion, foldable opposite side portions, top and bottom portions extending respectively from said webs, and upper extensions of said side portions that are foldable thereon, said upper extensions when folded back serving to support said top portion.

10. A combined container and display stand comprising a sheet of stiff material in the form

- of a blank having a rectangular body portion, opposite side portions whose top and bottom edges are inclined upwardly outward, and an upper, foldable portion, said side portions adapted to be folded behind said body portion with their side edges juxtaposed, to form an inclined seat at their upper edges, for said upper, foldable portion, and means of interengagement for said side portions, the bottom edges of said side portions and the bottom edge of said body portion co-acting to support the stand. 5
11. A combined container and display stand comprising a sheet of stiff material in the form of a blank having a rectangular body portion, provided with article engaging means, opposite side portions whose top and bottom edges are inclined upwardly outward, and an upper, foldable portion, said side portions adapted to be folded behind said body portion with their side edges juxtaposed, to form an inclined seat, at their upper edges for said upper foldable portion, and means of interengagement for said side portions, the bottom edges of said side portions and the bottom edge of said body portion co-acting to support the stand. 15
12. A combined container and display stand comprising a sheet of stiff material in the form of a blank having a rectangular body portion, opposite side portions whose top and bottom edges are inclined upwardly outward, an upper, foldable portion, and a lower foldable portion to serve as a base, said side portions adapted to be folded behind said body portion with their side edges juxtaposed, to form an inclined seat, at their upper edges, for said upper, foldable portion, and means of interengagement for said 20

13. A combined container and display stand comprising a sheet of stiff material in the form of a blank having a rectangular body portion, opposite side portions whose top and bottom edges are inclined upwardly outward, and an upper foldable portion, said side portions adapted to be folded behind said body portion with their side edges juxtaposed, to form an inclined seat at their upper edges for said upper, foldable portion, one of said side portions having a notch at its side edge and having a slit tongue, and the other side portion having a projecting tab to lodge in said notch and engage said slit tongue, the bottom inclined edges of said side portions and the bottom of said body portion co-acting to support the stand. 90
14. A combined container and display stand comprising a sheet of stiff material in the form of a blank having a rectangular body portion, foldable webs extending respectively from the sides, top and bottom of said body portion, foldable opposite side portions, top and bottom portions extending respectively from said webs, the top and bottom edges of said side portions being inclined upwardly outward, said side portions adapted to be folded behind said body portion with their side edges juxtaposed, to form an inclined seat at their upper edges for said foldable portion, and means of interengagement for said side portions, the bottom inclined edges of said side portions and the bottom of said body portion co-acting to support the stand. 100
